UNITED STATES PATENT OFFICE

114,998

DESIGN FOR AN ELECTRIC TABLE LAMP

Douglas F. Illian, Evanston, Ill.

Application April 7, 1939, Serial No. 84,102

Term of patent 7 years

To all whom it may concern:

Be it known that I, Douglas F. Illian, a citizen of the United States, residing at Evanston, in the county of Cook and State of Illinois, have invented a new, original, and ornamental Design for an Electric Table Lamp, of which the following is a specification, reference being had to the accompanying drawing, forming part thereof.

In the drawing:

The figure is a perspective view of the lamp, showing my new design.

I claim:

The ornamental design for an electric table lamp, as shown.

DOUGLAS F. ILLIAN.
